CLAIM

The ornamental design for a package that exposes a flashlight head as aircraft engine cowling, as shown.

DESCRIPTION

FIG. 1 is a perspective view of an open package that exposes a flashlight head as aircraft engine cowling, showing applicant's new design.

FIG. 2 is a right-side view of the open package.

FIG. 3 is a left-side view of the open package.

FIG. 4 is a bottom-up view of the open package.

FIG. 5 is a top-down view of the open package.

FIG. 6 is a front view of the open package.

FIG. 7 is a rear view of the open package.

FIG. 8 is a perspective view of the package when closed, exposing the flashlight head as the aircraft engine cowling.

FIG. 9 is a right-side view of the closed package.

FIG. 10 is a left-side view of the closed package.

FIG. 11 is a bottom-up view of the closed package.

FIG. 12 is a top-down view of the closed package.

FIG. 13 is a front view of the closed package; and,

FIG. 14 is a rear view of the closed package.

The broken lines shown represent portions of the package that exposes a flashlight head as aircraft engine cowling that form no part of the claimed design.

The package includes an opening through which the head of a flashlight is exposed. The opening is oriented in a drawing of an aircraft such that the head of the flashlight is positioned as engine cowling for the aircraft.
